[57] CLAIM

The ornamental design for a gaming pouch for Keno or the like, as shown and described.

DESCRIPTION

FIG. 1 is a perspective view of a gaming pouch for Keno or the like showing my new design;

FIG. 2 is an enlarged scale front elevational view with an intermediate portion of the strap omitted for convenience of illustration;

FIG. 3 is a right side elevational view thereof; and

FIG. 4 is a rear elevational view thereof showing the complete strap.

The short evenly-spaced dashed lines shown on the

drawing figures represent stitching.
